UNITED STATES PATENT OFFICE.

HARRY J. COYNE, OF WATERTOWN, MASSACHUSETTS.

METHOD OF MAKING MOTOR-VEHICLE BODIES.

Application filed June 7, 1926. Serial No. 114,238.

The present invention relates to a method of making motor vehicle bodies and more particularly to a method of this character especially applicable to the production of closed bodies with soft or non-metallic tops.

The building of this type of top according to existing methods requires both time and skill and not infrequently results in a lumpy or unsightly top due to displacement of the material with which the top is padded.

According to the present invention a top of superior appearance may be quickly produced at a minimum of time and cost and without the disadvantages inherent in existing methods. My method contemplates the production of a web of loosely matted, fibrous material of insufficient strength to permit considerable or sustained handling, securing to this loosely matted web a fabric support by means of stitching, cutting the thus reinforced web to the dimensions of the body to form a pad, securing the pad to the skeleton body structure with the fabric underneath and in engagement with the transverse top supports, and finally applying over the pad an outer cover of finish material. This may be secured at its margin in any desired manner. By virtue of this method several desirable results are accomplished. In the first place the loosely matted web may be produced of cotton, or similar fibrous material, cheaply and in large volume. It is preferable to form this web by a garnetting operation which enables the web to be delivered in any desired width and thickness. The web so produced, although incapable of severe or sustained handling, nevertheless is of sufficient strength to be connected by stitching to a reinforcing support or backing of fabric. Thus reinforced, the web may be maintained in the form of a roll until ready for use or may be immediately cut to the proper dimensions to form pads suitable for application to a body. The reinforcing support for the web may consist of any light and inexpensive fabric capable of supporting the web and assuming the strain of attachment of the finished pad to the skeleton body structure. A light cheesecloth or tobacco cloth has been found well suited for this purpose, the web being connected thereto by a plurality of spaced, longitudinal lines of stitching. The reinforced web cut to the proper dimensions and constituting a supporting deck pad is laid over the skeleton top and secured thereto

about its margin. The employment of the fabric backing permits the pad to be secured under sufficient tension to maintain it smoothly in place. After the application of the deck pad the finish material is applied and stretched taut thereover, this finish cover being also secured at its margin, the fasteners being preferably covered by the usual form of welt or beading.

In the accompanying drawings illustrating diagrammatically the several steps which complete the improved method,

Fig. 1 represents the formation of a loosely matted web of fibrous material;

Fig. 2 is the combining of this web with a reinforcing fabric backing through a plurality of seams;

Fig. 3 is a finished deck pad cut to the proper dimensions; and

Fig. 4 is the incorporation of the deck pad in an automobile top with a covering of finish material thereover.

According to the drawing, a loose web of cotton or similar fibrous material is produced by a garnetting operation as indicated generally in Fig. 1, the web being delivered from a conveyor 10 onto a transverse conveyor 12, the travel of which may be regulated to produce any desired width of web. In producing the web for the production of the motor vehicle tops, it is customary to form a web about fifty-four inches in width corresponding to the width of the top. After its completion the finished web is rolled in order to aid in handling and is thereafter combined, as indicated in Fig. 2, with a reinforcing fabric. The roll of web is shown at 14 and the roll of fabric combined therewith at 16. The two are passed over a supporting table 18 beneath a series of needles 20 which serve to form a plurality of seams or lines of stitches, uniting the web to the fabric in a manner which will be evident. In this form the reinforcing web may be handled in a roll or cut to the proper dimensions, as desired. Fig. 3 indicates such a reinforced web in the form of a finished deck pad. Thereafter the deck pad is superimposed over the skeleton frame 22 in an automobile top, this frame comprising the usual longitudinal supports 24 with cross braces 26. The longitudinal supports may if desired have wooden grounds 28 laid in recesses or grooves to provide an attaching base for the top material. The deck pad may be secured, if desired, at its margin to the ground and thereafter covered by finish ma-

terial 30 also secured at its margin to the ground 28 provided with a finish beading 32. With this form of construction the top may be simply and readily constructed of two parts consisting of the reinforced deck pad and the finish material secured to the skeleton frame. When so constructed it presents a neat and pleasing appearance, free from unsightly lumps or projections due to displacement of the pad.

Under certain circumstances it may be desirable to provide the web with a fabric backing on opposite sides. It will be evident, however, that the provision of this additional fabric reinforce does not alter or change the essential features of the invention. When the additional sheet of fabric is employed, both sheets of fabric are connected to the web in a single sewing operation.

20 What is claimed is:

1. A method of making motor vehicle tops which consists in producing a loosely matted web of fibrous material incapable of sustained handling and having a width at least 25 equal to the width of the opening in the top, connecting the loose fibrous web to a fabric backing support by stitching, cutting the thus

reinforced web into lengths commensurate with the length of the top opening to form individual pads, applying the pad to a skeleton top structure with the fabric support underneath and directly engaging with the structure, securing the pad to the structure, finally applying a finish cover over the pad, and securing the cover at opposite edges to maintain it in a taut condition bearing upon the yielding material of the pad.

2. An automobile top comprising spaced supports constituting a skeleton framework, a supporting fabric overlying the spaced supports and closing the opening in the top, the fabric being secured directly to the skeleton framework at its edges to maintain a taut condition, a loosely matted web of fibrous material stitched to the fabric and having sufficient thickness and resiliency to serve as a padding, and a finish cover superimposed over the padding and secured to the framework at its edges to maintain a taut condition in engagement with the fibrous material, the latter being supported by the connected fabric.
